US00D656334S

(12) **United States Design Patent**
Kumazawa

(10) **Patent No.:** **US D656,334 S**
(45) **Date of Patent:** **** Mar. 27, 2012**

(54) **CHAIR**

(75) Inventor: **Taku Kumazawa**, Aichi-ken (JP)

(73) Assignee: **Aichi Co., Ltd.**, Aichi-ken (JP)

(**) Term: **14 Years**

(21) Appl. No.: **29/355,484**

(22) Filed: **Feb. 8, 2010**

FIG. 1 is a perspective view of a chair showing my new design;

FIG. 2 is a front elevation view of the chair;

FIG. 3 is a rear elevation view of the chair;

FIG. 4 is a left side elevation view of the chair;

FIG. 5 is a top plan view of the chair; and,

FIG. 6 is a bottom plan view of the chair.

The right side elevation view of the chair is a mirror image of the left side elevation view thereof.

All structures represented in broken lines are not part of the design sought to be patented.
